UNITED STATES PATENT OFFICE.

HERMANN LUDWIG PAUL CARL HARTMANN, OF BAY RIDGE, NEW YORK.

FREIGHT-CAR.

SPECIFICATION forming part of Letters Patent No. 393,229, dated November 20, 1888.

Application filed July 16, 1888. Serial No. 280,032. (No model.)

To all whom it may concern:

Be it known that I, HERMANN LUDWIG PAUL CARL HARTMANN, a subject of the Emperor of Germany, at present residing at Bay Ridge, in the county of Kings and State of New York, have invented a new and Improved Freight-Car, of which the following is a full, clear, and exact description.

The improvement consists in providing a box freight-car with doors and means for operating and securing them, as hereinafter described and claimed.

Reference is to be had to the accompanying drawings, forming a part of this specification, in which similar letters of reference indicate corresponding parts in all the figures.

Figure 1 is a side elevation of the improvement, showing the doors closed. Fig. 2 is a similar view of one end of the improvement, showing the doors open; and Fig. 3 is a transverse section of the improvement on the line *xx* of Fig. 2.

The car *A* is provided on one or both sides with the doors *B* and *C*, extending the entire length of the car. The door *B* is hinged at its upper end to a beam, *D*, of the car-body, and the door *O* is hinged at its lower end to a beam, *E*, of the car-body. When the doors *B* and *C* are closed, they completely close the respective sides of the car *A*, as is plainly shown in Fig. 1.

The doors *B* and *C* are provided with hinge-pivots *G G'* and *H H'*, respectively, projecting at the ends of the car and carrying the pulleys *I I'* and *J J'*, respectively. Over the pulleys *I* and *J* passes a chain, *K*, secured by one end to the pulley *I*, wound several times around the said pulley, and then over and around the pulley *J*, and then the chain is again passed over the pulley *I* and hangs down from the same, being provided at its lower end with a ring, *K'*, for taking hold of the said chain. The chain *K'* is similarly fastened by one end to the pulley *I'*, wound several times around the same, passed over the pulley *J'* and wound around the same, and then passed up again over the pulley *I'*, hanging down in the same manner as the chain *K*, and also provided with a ring, *K''*.

On the inside of the top of the car *A*, on one or both sides, is held a longitudinal beam, *L*, on which are pivoted the downwardly-extend-

ing posts *N* and *N'*, reaching at their lower ends onto the floor of the car *A*, as is plainly shown in Fig. 3. Against the posts *N* and *N'* 55 lean the doors *O*, *O'*, and *O''*, pivoted at their lower ends to the floor of the car and adapted to swing outward, as is plainly shown in Figs. 2 and 3. The doors *O*, *O'*, and *O''* can be secured in their uppermost position, as shown 60 in Fig. 3, by means of bolts *P* or other suitable locking devices held on the posts *N*. The posts *N*, when disengaged from the doors *O*, *O'*, and *O''*, can be swung upward against the under side of the longitudinal beam *L* and locked 65 in position by a hook, *Q*, engaging a staple, *R*, on the said post *N*, as is plainly shown in dotted lines in Fig. 2.

The operation is as follows: When the doors *B* and *C* are in a closed position, as shown in Fig. 1, they are locked in place by a suitable locking device, *F*, of any approved construction. When the operator desires to open the doors, he unlocks the locking device *F* and pulls on either of the chains *K* or *K'*, whereby 70 the doors *B* and *C* are forced to swing open by the action of the chains *K* or *K'*, respectively, on the pulleys *I J* or *I' J'*, respectively. The door *B* swings upward into the position shown in Fig. 3, and the door *C* swings downward, 75 as is plainly shown in the said figure. The door *C* is preferably made somewhat heavier than the door *B*, so that the opening of both doors *B* and *C* takes place without much pulling by the operator on the respective chain *K* 80 or *K'*. When both doors are open, the entire side of the car *A* is open, and the operator can unload from the middle or from either end of the car, as desired. The operator may also swing down either of the doors *O*, *O'*, or *O''* by 85 loosening the bolts *P*, held on the posts *N* and *N'*. When the operator desires to place long articles—such as logs, &c.—into the car, he not only opens the side doors, *B* and *C*, but also opens all of the doors *O*, *O'*, and *O''*, and he 90 swings the posts *N* and *N'* upward, locking the same in an uppermost position by the hooks *Q* engaging the staples *R* on the said posts. The entire side of the car is then open, and articles of the same length as the car can be 95 easily placed in the same or removed from the car.

The door *C*, instead of being hung vertically, as shown in Fig. 3, may be placed horizontally

- on suitable supports—such as the wagon-body—from which articles are loaded into the car, or on which articles may be placed from the car. When the door C is in such a horizontal position, the door B is in a like position, as they operate simultaneously on account of the connection by the chains K and K' with the respective pulleys I I' and J J' of the said doors B and C.
- Having thus described my invention, what I claim as new, and desire to secure by Letters Patent, is—
1. The combination, with a box-car body, of two doors extending the length of the same, one of the said doors being pivoted at its upper end to the top of the car-body and the other at its lower end to the bottom of the car-body, pulleys secured at the hinges of the said doors,

and chains wound around the said pulleys for opening and closing the upper and lower doors 20 simultaneously, substantially as shown and described.

2. The combination, with the box-car body and two outer doors, of the posts N, hinged to the top of the same and hanging normally vertical, doors O O' O'', which are hinged to the floor of the car contiguous and parallel to the outer doors, and fastening-bolts P, as shown and described, whereby the inner doors are adapted to rest against and be secured to the 30 posts when raised, as specified.
